UNITED STATES PATENT OFFICE.

LOUIS V. ARONSON, OF NEWARK, NEW JERSEY.

CHANGEABLE EXHIBITOR.

Application filed October 16, 1926. Serial No. 142,024.

The invention relates to changeable exhibitors, and has as an object the provision of a device of this nature which, by means of a reciprocating part, shifts the exhibited card from a lower to an upper position, and upon the return of the reciprocating part shifts a card from an upper to a lower position.

An object of the invention is to provide a device that will successively exhibit each card of a series in rotation.

A further object of the invention is the provision of a changeable exhibitor which may be used as a calendar to exhibit in turn the numbers of the days of the month, or which may be used to likewise exhibit a plurality of advertising cards.

A further object of the invention is the provision of a device of the character described having means to prevent the reversal of movement of the reciprocating part until after a full stroke thereof has been made.

A further object of the invention is the provision of a device of this character in which the cards are held in position for shifting during movements of the reciprocating part.

A further object of the invention is the provision of a device of this character of exceedingly simple mechanism.

Further objects of the invention will appear from the following description when read in connection with the accompanying drawings, wherein

Figure 1 is a perspective view of a desirable form of the device;

Fig. 2 is a vertical section of the upper portion of the casing showing the mechanism in elevation;

Fig. 3 is a vertical section of the casing on line 3—3 of Fig. 2 showing an edge view of the mechanism within the casing;

Fig. 4 is a view similar to Fig. 2 showing a rear view of the mechanism within the casing;

Fig. 5 is a vertical section on line 5—5 of Fig. 3 showing a rear view of the mechanism with the plate of the reciprocating part removed, and with the reciprocating part in its upper position;

Fig. 6 is a vertical section on line 6—6 of Fig. 2;

Fig. 7 is a plan view with the casing removed;

Fig. 8 is a horizontal section on line 8—8 of Fig. 2 with the casing removed;

Fig. 9 is a section on line 9—9 of Fig. 3, showing the interior of the casing and parts carried thereby;

Fig. 10 is a detail perspective view of the frame of the device;

Fig. 11 is a detail perspective view of the reciprocating member, and

Fig. 12 is a detail perspective view of one of the card holding clips.

As shown in Fig. 1, the device comprises a base 20 and a casing 21, shown in a desirable form for a calendar. As shown in this figure, there is an opening 22 through the casing wherein the exhibited card may be viewed, and a pocket 22' in which a pack of slips may be inserted, having an opening 23 in its front through which the outer slip may be viewed. When used as a calendar, it is to be understood that the package of slips may contain a slip for each month of the year, which slip may be removed and the desired month brought to the outside of the pack, after which the slips may be reinserted in the pocket.

The card holding and shifting mechanism comprises a frame 24, shown in perspective view in Fig. 10, and comprising uprights 25, 26, in spaced relation, and is held by transverse members 27, 28, 29, between which members the cards to be exhibited may be contained, one-half in each space, a card being shifted from the lower to the upper space upon the upward movement of the reciprocating member, and a card from the other side of the pack may be shifted from the upper to the lower space upon return of the reciprocating member.

The frame 24 further comprises a pair of ears 30, 31, for support of the frame upon the base 20 in the manner disclosed in Fig. 2.

As shown, the casing 21 has inturned ears 32, 33, overlying the base 20, and which may be secured thereto by means of screws 34 insertable from below. The casing 21 further comprises upper inturned ears 35, 36 adapted to project inwardly into contact with the upper end of the tops of the members 25, 26 of the frame 24, and a cap 37 may be secured

to the body of the casing, as by screws 38, 39, engaging the ears 35, 36.

The frame 24 further comprises integral lugs 40, 41 at their upper end and like lugs 42, 43 at the opposite side of the lower ends for support of the spring pressed fingers to be described.

The reciprocating member of the device shown in perspective in Fig. 11, comprises a frame made up of side plates 44, 45 and end plates 46, 47, the plate 44 having projecting ears 48, 49 at its lower end and ears 50, 51 at its upper end. The plate 45 is formed exactly as is plate 44 in inverted position.

To engage the edges of cards and shift the same the ears 48, 49 are shown as folded upon themselves to provide portions 52, 53 projecting into the plane of the cards to move the card upwardly as the frame rises, the plate 45 having like portions 54, 55 to engage the upper edge of the card upon the reverse side of the frame to shift the card downwardly in the downward movement of the frame.

To produce movement of the frame there is shown a button 56 projecting through a slot 57 in the rear of the casing, and having screw threaded engagement with a boss 58 carried by the rear plate 45. The button 56 may be removed in the dismantling of the casing from the mechanism.

To provide continuous pressure to the rear, upon the upper cards, there are shown a pair of fingers 59, 60 pivoted upon a rod 61, passing through the openings in the lugs 40, 41, there being coil springs 62, 63 anchored upon the rod 61 and having projecting ends 64, 65 pressing against the integral lugs 66, 67 projecting from the fingers 59, 60. At the bottom of the rear of the device fingers 68, 69 are pivoted upon a rod 70 mounted in the lugs 42, 43, there being springs 71, 72 acting in the same manner as springs 62, 63.

The fingers 59, 60 and their operating mechanism are duplicates of the springs 68, 69, and the latter operating to press the lower pack of cards forward in exactly the same manner as the upper fingers press the upper cards rearwardly.

As the frame 45 is forced upward the shorter finger 68 will first raise over the narrowed portion 73 of the plate 45. At this time the finger 69 will still be in contact with the rear card of the lower pack to press the pack forward, and when the narrowed portion 73 of the plate 45 has passed the lower finger it will return to contact with the card and the narrowed portion 73 will then pass under the finger 69 whereby the card will at all times have the pressure of at least one of the fingers and maintain the pressure forward of the cards in the pack. In its upward movement, the frame will first pass under the spring 60 by virtue of

the cam surface 74, the short upper spring 59 at this time preserving the pressure rearwardly upon the upper pack, and when the narrowed portion 73 of the plate 44 has passed the long finger 60 it will return into contact with the card, after which the short finger 59 will be lifted by the package thereunder of the narrowed portion 73.

The side members 25, 26 are of the same thickness as the thickness of the pack of cards in the upper or lower space. The pack has one more card below than above during the normal position of the device, and one more card in the upper space at the limit of upward movement of the sliding frame. The cross members 27—28—29 are of a width sufficient to stand the thickness of a card inward from the edges of the upright members 25, 26 at both front and rear edges of these members to permit of the passage of the card within the width of the uprights 25—26.

To hold the cards in the space between the cross members 27—29, during movement of the reciprocating member, there are shown clips 76—76', normally lying in contact one with the upper surface of the member 29, and the other in contact with the lower surface of the member 27, having ears 77—78, projecting downwardly and overlapping the surfaces of the cards, as clearly shown in Fig. 6, whereby the cards are retained in the space between the transverse members and against the pressure of the fingers 59, 60, and 68—69.

The clips 76 are desirably pivoted upon the members 27, 29 by means of ears, 79, 80, adapted to project downwardly into openings 81, 82 in said members, and the clips are pressed toward the surface of the members by means of a spring 83 at the top, and a spring 84 at the bottom anchored to the inner surface of the members 25, 26, as shown at 85, 86.

In the normal position of the device shown in Figs. 2, 3 and 6, the portions 52, 53 of the side plates underlie the lower edge of the outside card, the clip 76' at the bottom being then depressed, as shown in Fig. 2, by contact with the edge of the plate 44 at its reduced portion 87. When the frame 45 is raised the upper clip 76 is lifted in exactly the same manner. When the upper or lower clip is thus raised out of clipping contact with the card the pressure of the spring fingers 59, 60 or 68, 69 will force the card toward the opposite side over the members 52, 53 or 54, 55. The subsequent reciprocation of the frame 45 then shifting the card either upwardly or downwardly, in accordance with its direction of motion.

To prevent a partial stroke of the reciprocating frame 45 whereby a card might be raised part way and the reciprocating member then be lowered to permit the feed of a

subsequent card, there is shown a serrated plate 88, shown as carried by the interior surface of the rear wall of the casing, and a trigger 89 is pivoted upon the boss 58, 5 which trigger has a finger 90 held in the position shown in Fig. 4, by means of a spring 91 acting in tension, anchored as at 92. As the trigger 89 is carried upwardly, the finger 90 wipes over the serrations of 10 the plate 88, assuming the diagonal position shown in 89, which effectually prevents downward movement of frame 45 until the frame has been carried to the top of its stroke allowing the trigger to pass the upper 15 serrations of the plate 88, at which point the normal position of Fig. 4 is resumed. The upward stroke of the plate is then complete, and upon its downward stroke the trigger 89 assumes a reverse diagonal position effectually preventing return upward of the frame 45 until the downward stroke of the frame has been completed.

To cover the slot 57 in the rear of the casing, there is shown a plate 93 pivoted to the 25 interior of the casing, as at 94, and spring pressed to the position shown in Fig. 9 by means of a spring 95 anchored at 96 to the casing. Upward movement of the boss 58 acting against the cam surface 97 will 30 stretch the spring 95 to allow passage of the boss, the plate 93 passing through the dotted line position in Fig. 9 and returning to the position, covering the slot upon the subsequent downward stroke of the boss 58. 35 It will be seen that the mechanism is duplicated at the two ends of the frame 25, and that with the exception of the presence of the boss 58 the frame 45 might be reversed in its position upon the frame 25 and be 40 fully operable. While the frame is shown as arranged vertically, it is obvious that since the attraction of gravity upon the cards has no function, the frame can be arranged horizontally without necessary changes in 45 mechanism. The frame 45 may be reciprocated in any desired manner, and the device may be used not only as a calendar, but in an enlarged size for advertising display of cards. The operation of the device will be 50 clear from the above description.

Minor changes may be made in the physical embodiment of the invention without departing from the spirit thereof within the scope of the appended claims.

55 I claim—

1. A changeable exhibitor comprising, in combination, means to support packs of cards in mutually edgewise relation, means to press the cards in said packs in opposite 60 directions respectively, reciprocating means surrounding said first named means and telescoping with said packs acting to shift cards alternately from one pack to another during reciprocation, means normally holding the 65 cards from movement under action of said

pressing means and removed from action by engagement with said reciprocating means.

2. A changeable exhibitor comprising, in combination, a frame having spaces to enclose packs of cards in common planes, a 70 member surrounding and reciprocating on said frame, means at diagonally opposite points on said member to engage an edge of the outer card of a pack whereby to shift a card from pack to pack upon each movement, and means to retain the packs in said spaces between movements of said member. 75

3. A changeable exhibitor comprising, in combination, a frame having spaces to enclose packs of cards in common planes, a 80 member surrounding and reciprocating on said frame, means at diagonally opposite points on said member to engage an edge of the outer card of a pack whereby to shift a card from pack to pack upon each movement, means to retain the packs in said spaces between movements of said member, and means whereby said retaining means are withdrawn from action at the limits of reciprocation of said reciprocating member to 85 permit said edge engaging means to contact a card.

4. A changeable exhibitor comprising, in combination, a frame having spaces to enclose packs of cards in common planes, a 90 member surrounding said frame and reciprocating thereon, having an opening through a side thereof for viewing of a card of one of said packs, a plurality of fingers of varying lengths, springs to press one set of said 95 fingers against each of said packs of cards located upon opposite sides of the frame, cam surfaces upon said fingers whereby to lift said fingers from said cards upon passage of said member thereunder successively 100 whereby at least one of said fingers is at all 105 times in contact with the outer card of each pack to press the pack toward the opposite side of the frame, means carried by the member to engage an edge of the outermost 110 card of each pack upon successive movements of reciprocation whereby to shift a card from one pack to the other alternately upon each movement of reciprocation of the member. 115

5. A changeable exhibitor comprising, in combination, a frame having spaces to enclose packs of cards in common planes, a member surrounding said frame and reciprocating thereon, having an opening through a side thereof for viewing of a card of one of said packs, a plurality of fingers of varying lengths, springs to press one set of said fingers against each of said packs of cards located upon opposite sides of the frame, 120 cam surfaces upon said fingers whereby to lift said fingers from said cards upon passage of said member thereunder successively 125 whereby at least one of said fingers is at all times in contact with the outer card of each 130

pack to press the pack toward the opposite side of the frame, means carried by the member to engage an edge of the outermost card of each pack upon successive movements of reciprocation whereby to shift a card from one pack to the other alternately upon each movement of reciprocation of the member, clips carried by the frame normally

overlapping each side of each pack to retain the cards within the frame against pressure of said fingers, and means whereby a clip is withdrawn from gripping relation with the cards at the extreme position of reciprocation of the member. ¹⁰
